Attorney

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed July 25, 1924. Serial No. 728,075.

This invention relates to gages or devices for locating work-sheets in a typewriting machine.

In many cases it is desired to type only 5 one line upon a work-sheet, then remove it and replace it by a fresh sheet which is to be typed upon only one line, and so on.

One of the objects of the present invention is to provide convenient means for adapting 10 the typewriting machine to different kinds of work. For some kinds of work the line of writing, or at least the first line, necessarily occupies one position, while in other kinds of work the first line necessarily occupies 15 another position upon the work-sheet. It is usual to provide a gage for the end of a work-sheet, but much time is consumed in readjusting the gage for different kinds of work from time to time.

20 To overcome this difficulty, this invention provides one main gage having a certain relation to the printing point on the typewriter, so that when the sheet is inserted and placed against said gage, it will be in a 25 position to receive the first line of typing thereon, and having a second gage between the main gage and the platen, these gages to be used each to the exclusion of the other, the intermediate gage being movable out of 30 the way when it is desired to use the main or remote gage. Hence the machine is readily adjusted for the two kinds of work, and it will only be necessary to shift the intervening gage into or out of position.

35 Preferably the main gage is also movable into and out of position, the two gages being preferably mounted on a single rocking frame, and in order to bring either gage into use it is only necessary to rock said frame.

40 Other features and advantages will hereinafter appear.

In the accompanying drawings,

Figure 1 is a perspective view of a part 45 of an Underwood typewriting machine, embodying the present invention, parts being broken away.

Figure 2 is a sectional view taken on the plane indicated by the line A—A and looking in the direction of the arrows.

50 Figure 3 is a sectional detail view, showing the main and intermediate gages formed of a single piece of metal and mounted on a common shaft.

Figure 4 is a view similar to Figure 2 with the intermediate gage in effective position.

Figure 5 is a sectional detail view, showing the intermediate gage held in effective position by a spring clip.

Figure 6 is a sectional detail view taken on the plane indicated by the line B—B of figure 1.

Figure 7 is a view of a work-sheet showing the writing lines located at different horizontal and vertical planes on the sheet.

The platen 1 is provided with an axle 2 which is journaled in the platen-frame 3. A work-sheet 4 may be inserted around the platen 1 carrying it up from the rear so that it engages the pressure-rolls 5. The platen 1 may be rotated by the usual finger-wheel 6 to advance the work-sheet 4 past the printing point, indicated by the type-bar 7, and upwardly. To position the work-sheet 4 accurately to bring its writing line 8 (see Figure 7) level with the printing point, it is customary to provide a gage for the work-sheet against which its end touches. This end gage is shown in the present invention as a pair of finger-pieces or stops 9 on the introductory table 10, which is located to the rear of the platen.

This rear table 10, is hinged at 11, to the side frames of the carriage. The table 10 is supported adjustably upon a pair of arms 12 which are secured to the platen-frame 3 by the screws 13. The slots 14 and the screws 15, operating therein, afford the adjustable connection between the arms 12 and the table 10. By reason of this construction 90 said table 10 may be moved up or down to adjust it to the needs of the operator, and also to true it relatively to the printing line.

95 Mounted securely on the table 10, on one side thereof, and extending substantially its entire length is a side gage 16 made of metal against which the side edges of the work-sheet 4 ride in order to guide the sheet in its vertical movement. This side gage comprises a flat portion 17 and an upwardly 100 projecting flange 18.

The single end gage, comprising the finger-pieces or stops 9, is serviceable when work-sheets with their writing lines occupying the same position on the sheet are inserted. When work-sheets for a different

kind of work, having their writing lines located at a different point thereon, are inserted, it would be necessary to readjust this single gage. This would take considerable time and is difficult. The present invention eliminates this waste of time and trouble. This is accomplished by providing a second end gage which is movable into ineffective position when the first end gage is used.

This second end gage is located at the rear of the table 10 and at the point below the first end gage. It comprises a pair of brackets 19 secured to the rear of the table 10 by means of the screws 20. Mounted to rock in these brackets 19 is a shaft 21 upon which is fixedly mounted frames 22. On each of the frames 22 is secured a metal strip 23 having an angular extension forming a finger-piece or stop 24. Each of these finger-pieces 24 are directly behind and in alignment with a slot 25 in the table 10. The finger-pieces 24 are held away from said slots 25 by a spring-clip 26 co-operating with the metal strip 23. This spring-clip 26 is mounted only in the bracket 19 located on the left side of the table 10. When the uppermost gage is in use the finger-pieces 24 are held away from the slots 25 and behind the table 10 by the spring-clip 26. When the work-sheet for work of a different character is inserted in the machine and it is necessary to use the second end gage, the finger-pieces 24 may be swung forwardly through the slots 25 to the front of the table 10 as shown in Figure 4. This is accomplished by turning the knob 27 fastened to the rock-shaft 21. When the upper end gage is to be used again, the second end gage is swung rearwardly by means of the knob 27.

While the upper end gage comprising the finger-pieces 9 may be formed on the table 10 as shown, it is preferred that this gage also be movable into and out of effective position. This is accomplished as shown in Figure 3, wherein the metal strip 23 is extended and terminates in a finger-piece or stop 28 similar to the finger-piece 24. Thus the two end gages may be stamped from a single piece of metal. The finger-piece 28 is located directly behind and in alignment with the slot 29 in the table 10. By reason of this construction, when the knob 27 is turned to swing the finger-piece 28 through the slot 29 into effective position, the lower finger-piece 24 is simultaneously swung rearwardly out of effective position. When either of said gages is swung into effective position it is held there by the spring-clip 26.

While only a main gage and an intermediate gage are illustrated and described, it is obvious that two or more intermediate gages might be provided to give the machine a greater range of adaptability.

Variations may be resorted to within the scope of the invention, and portions of the improvements may be used without others.

Having thus described my invention, I claim:

1. In a typewriting machine, in combination, a rotatable platen, a table for holding a work-sheet, a side gage for guiding the movement of said sheet, an end gage for positioning a work-sheet having a writing line occupying one position thereon, and another end gage for positioning a work-sheet having a writing line occupying a different position thereon, both of the two latter gages being movable into and out of effective position. 70

2. In a typewriting machine, in combination, a platen, a table for holding a work-sheet, a side gage for guiding the movement of said sheet, an end gage for positioning a work-sheet having a writing line occupying one position thereon, a second end gage for positioning a work-sheet having a writing line occupying a different position thereon, and means for moving either of the two latter gages into or out of effective position. 85

3. In a typewriting machine, in combination, a rotatable platen, a table for holding a work-sheet, an end gage for positioning a work-sheet having a writing line occupying one position thereon, a second end gage for positioning a work-sheet having a writing line occupying a different position thereon, 90

a frame carrying both of said end gages, a shaft supporting said frame and mounted to rock, and a knob on said shaft to rock the same. 95

4. In a typewriting machine, in combination, a rotatable platen, a table for holding a work-sheet, a side gage for guiding the movement of said sheet, an end gage for positioning a work-sheet having a writing line occupying one position thereon, a second end gage for positioning a work-sheet having a writing line occupying a different position thereon, and a device for holding either of the two latter gages in effective or ineffective position. 105

5. In a typewriting machine, in combination, a rotatable platen, a table for holding a work-sheet, a side gage for guiding the movement of said sheet, an end gage for positioning a work-sheet having a writing line occupying one position thereon, a second end gage for positioning a work-sheet having a writing line occupying a different position thereon, both of said end gages mounted on a common rock-shaft, and a spring-clip co-operating with said rock-shaft to hold either of said gages in effective or ineffective position. 110

6. In a typewriting machine, in combination, a platen, a table for holding a work-sheet, an end gage for positioning a work-sheet having a writing line occupying one 120

position thereon, and a second gage for positioning a work-sheet having a writing line occupying a different position thereon, both of said gages being formed of a single strip 5 of metal.

7. In a typewriting machine, in combination, a platen, a table for holding a work-sheet, said table having a slot adjacent its top end, brackets secured to the rear of 10 said table, a shaft mounted rockingly on said brackets, a frame mounted fixedly on said shaft, and a strip of metal secured to said frame, said strip having a finger portion in alignment with the slot in the table adjacent its top and adapted to pass therethrough to serve as an end gage, and said strip having a second finger portion in alignment with the slot in the table 15 intermediate its ends to pass therethrough to serve as an end gage, and a knob fixed to said shaft to rock either of said finger portions through its aligned slot.
8. In a typewriting machine, in combination, a platen, a table for holding a work-sheet, said table having a slot adjacent its top end and a second slot intermediate its 20 ends, brackets secured to the rear of said

table intermediate said slots, a shaft mounted rockingly in said brackets, a frame mounted fixedly on said shaft, a strip of metal secured to said frame, said strip having a finger portion in alignment with the slot in the table adjacent its top and adapted to pass therethrough to serve as an end gage, and said strip having a second finger portion in alignment with the slot in the table 25 intermediate its ends to pass therethrough to serve as an end gage, and a knob fixed to said shaft to rock either of said finger portions through its aligned slot.

9. In a typewriting machine, in combination with a table for holding a work-sheet, a plurality of end gages carried by said table, said gages so arranged with respect to said table that only one gage is effective at one time.

JESSE A. B. SMITH.
